PAGE 2

FIG. 2

FIG. 3

FIG. 4

Fig. 1 is a side perspective view of a tractor showing our new design.

Fig. 2 is a top perspective view being taken from a point rearwardly of the tractor.

Fig. 3 is a side elevational view.

Fig. 4 is a front elevational view.

The essential features of our design reside in these portions shown in full lines.

We claim:

The ornamental design for a tractor, as shown and described.
